O. B. PECK, JR

PLANT FOR CENTRIFUGAL CONCENTRATION OF ORES AND LIKE MATERIALS

Filed June 23, 1924

2 Sheets-Sheet 2

Orrin B. Peck, Jr.

UNITED STATES PATENT OFFICE.

ORRIN B. PECK, JR., OF LOS ANGELES, CALIFORNIA.

PLANT FOR CENTRIFUGAL CONCENTRATION OF ORES AND LIKE MATERIALS.

Application filed June 23, 1924. Serial No. 721,647.

To all whom it may concern:

Be it known that I, ORRIN B. PECK, Jr., a citizen of the United States, and resident of the city of Los Angeles, State of California, have invented certain new and useful Improvements in Plants for Centrifugal Concentration of Ores and like Materials, and my invention preferably has in its embodiment that class of concentrator which 5 operates in successive cycles of alternately accumulating a quantity of concentrates in a rotatable concentrating vessel and then discharging the same during reduced rotation, and the combination of elements in 10 automatic association and operative coordination to carry out the successive steps 15 of such cycles in requisite relative harmony to obtain the results sought.

In the drawings, Fig. 1 is mainly a top 20 plan showing the relative association of elements of my invention, but with some portions partly in section and some not fully illustrated in detail, also with certain concentrating elements positioned for the beginning of a cycle of operation.

Fig. 2 is partly a vertical longitudinal central section and partly a side elevation of the concentrating machine with its feed mechanism, with parts positioned as at the 30 end of the concentrating period of a cycle, ready for commencement of discharge of accumulated concentrates.

Fig. 3 is a side elevation of the divided or two part counter shaft for driving the 35 concentrator, with its clutch and brake as well as some other attached parts, the clutch being illustrated as out of transmission engagement, while part of the brake is illustrated in section and in position for braking engagement.

Fig. 4 is a central vertical section of the feed valve and its hydraulic operating cylinder, shown functioned to position for feed of material to the concentrator, as would 45 be the case while the concentrator parts are positioned as in Fig. 1, at the beginning and throughout the entire concentrating period of the cycle.

Fig. 5 is a cross section of Fig. 4 on line 50 5-5, Fig. 4, looking in the direction of the arrows, especially showing the comparatively small hole through the piston head.

Fig. 6 is mainly a vertical cross section

of the automatic control member, taken mostly on line 6-6, of Fig. 1, looking in 55 the direction of the arrows, but revolved to a position relatively 180°, showing the mechanism more complete than in Fig. 1 and as just having functioned for commencement of the concentrating period of 60 a cycle of operation.

Fig. 7 is similar to Fig. 6, only illustrating the position of its members shortly before having functioned as illustrated in said Fig. 6.

Fig. 8 is a fragmentary side elevation of the upper left hand portion of Fig. 6, illustrating the outer end of the valve lever and its associate parts at this end, raised to its fullest extent, in position to be released for 70 downward movement to close its valve, also showing in dotted lines the manner of connection of the valve stem head and the lever.

Fig. 9 is a top plan of one of the graduated control cylinders enlarged, which are 75 shown without complete detail in the automatic control member of Fig. 1, where in the interest of clarity of illustration, the actuating members have been mostly omitted.

Fig. 10 is a development of the circumferential surface of Fig. 9.

Fig. 11 is a central plan section of Fig. 9, with two of the movable actuating members mounted on it.

Fig. 12 is a plan of one of the actuating members, detached from the control cylinder, and its fastening bolt, the latter having an elongated head.

Fig. 13 is the governor and its driving 90 clutch, illustrated partly in section and partly in elevation, showing the governor at rest, with closed port as it appears in Fig. 1, during the concentrating period.

Fig. 14 shows a side elevation of the brake 95 friction wheel mounted on the part of the shaft which drives the concentrating vessel, and a cross section of the lower part of the brake mechanism with its parts in position of having moved the brake out of 100 frictional engagement, as would be the case while the governor is in position illustrated in Figs. 1 and 13.

Fig. 15 is similar to Fig. 13, except the governor driving clutch is in engagement, operating the governor to open its 105

liquid flow port in position it would be to a greater or less extent during the concentrate discharge period of the cycle.

Fig. 16 is similar to Fig. 14, but with the moving parts of the brake mechanism in position as they would be while the associated governor is in operation as illustrated in Figs. 3 and 15.

Fig. 17 is mostly a central cross section 10 of the lower part of the brake members, and a side elevation of its other parts, illustrated in position revolved 90° with respect to Fig. 16.

Fig. 18 is mostly a cross section of the 15 governor drive clutch, taken on line 18—18 of Fig. 15.

I wish to first explain that in the accompanying drawings, to enable greater clearness of illustration and understanding, the 20 relative sizes and proportions of some elements and members are not maintained as they might best be employed in operation, and that in some instances the illustrations 25 of elements are not complete in detail throughout all figures, but are in the aggregate, sufficiently so to render a complete understanding of my invention, and its operation, as well as to enable its construction.

In carrying out my invention I employ a 30 centrifugal concentrating machine preferably of the kind and type illustrated and described in application for U. S. Letters Patent recently filed by me, which operate in successive cycles of accumulating a quantity 35 of concentrates or heavier constituents, in a concentrating vessel while rotating at a comparatively high rate of speed, and then discharging the same while revolving at a comparatively low rate of speed, together 40 with mechanism, members, elements and parts for best relatively and concurrently coordinating and functioning to automatically effect the various steps in the successive cycles of operation to obtain highest 45 mechanical and technical results.

In the drawings, 2 is a rotatable concentrating vessel, which in Fig. 1 is shown partly in horizontal section and in Fig. 2, partly in vertical section. It is preferably 50 smallest at its feed end and otherwise of the same general form and structure illustrated.

The vessel is provided with a head 3, at its small end, having an extended hollow 55 trunnion by which this end is rotatably journaled in a box 4. It is also provided with a head 5 at its large end, which is securely and concentrically mounted on the end of a hollow shaft 6, which, in turn, is 60 rotatably journaled in boxes 7 and 8, as shown, and is provided with a pulley 9, by which rotation may be imparted to the shaft and vessel, as desired.

Within the vessel is a rotatable core 10, 65 which is securely mounted on the overhang-

ing end portion of a shaft 11, this latter shaft passing into the vessel through the hollow shaft, in which it is journaled, and its outer or opposite end portion is journaled in a box 12. The shaft is provided 70 with a pulley 13, by which it, with the core, may be revolved.

It is preferable to shape the circumference of the core, tapering to conform to that shape of the vessel, and to make it somewhat shorter than the internal length of the vessel, also of diameter so when the same is positioned in the vessel near the small or feed end, as shown in Fig. 1, there will be a comparatively small space 14, between the 80 circumferential surface of the core, and the internal diametrical surface of the vessel. Both of these surfaces are best when made comparatively smooth so the space 14, Figs. 1 and 2, which serves as the material flow 85 channel and concentrating passage, will be comparatively uniform.

It will be understood that in operation, for the commencement of the concentrating period of each cycle, the core is positioned 90 at the small or feed end of the vessel, as is shown in Fig. 1, which contracts the concentrating passage, being also the flow channel to its smallest size, and as the concentrating period proceeds, the progressive separation and lodgment of concentrates in the channel, begins to contract such channel and commences to back up or increase the accumulation of liquid and material in the feed end of the vessel, immediately resulting in 100 an increased pressure of such materials lengthways on the core to push or force the core towards the discharge end of the vessel, in such way enlarging the flow channel 14, and automatically lessening the endways 105 pressure on the core so as to maintain the size of the flow channel and separating passage practically constant.

To neutralize or counterbalance the pressure on the core towards the discharge end 110 of the vessel, there is provided a hydraulic pressure cylinder 15, which may be securely attached to the outer end of the journal stand 16, as illustrated in Figs. 1 and 2. This cylinder is preferably positioned in extended axial alignment with the core shaft 11, and is of internal finish suitable for an appropriate piston head 17, to operate therein.

The piston head while intended not to rotate in the cylinder, rotatably engages a disc 18, which is secured to the contracted end portion of the shaft 11, the shaft extending through the journal box 12 into the cylinder 15, for this purpose, as best shown in Fig. 1.

To afford suitable yieldable hydraulic resistance in the cylinder to the endways pressure on the core, and at the same time permit desired longitudinal movement towards 130

- the large end of the vessel during the concentrating period, as well as to force the core back to the small end of the vessel during the concentrate discharge period of the cycle, I provide it with a suitable yieldable, and preferably adjustable source of water or other liquid supply under pressure, as from a suitable accumulator, or air cushioned receiver 19, which is shown in Fig. 2. 5
- 10 This accumulator should be of adequate size, and may be located at any convenient place with respect to the cylinder 15, to which it is connected by a pipe 20. The liquid in the accumulator should be maintained at as nearly uniform pressure as practicable, to furnish requisite and desired pressure in the cylinder 15, to suitably balance the opposing endway pressure on the core. The pressure to the cylinder 15, may be 15 further adjusted by a relief or blow off valve 21, of any suitable type. To enable better description and illustration, the pipe connections to and from the cylinder 15, are shown relatively positioned 90° differently 20 in Figs. 1 and 2.
- 25 In operation, the length of the concentrating period of the cycle is not predetermined, it commences with the core positioned at the small end of the vessel, as above stated, and as shown in Fig. 1, and continues until the core has been gradually forced to its extreme position at the large end of the vessel, as shown in Fig. 2, and as hereinafter explained at which time 30 this period is complete, feed of material to the vessel for concentration is then discontinued; relatively clean water introduced in place of material; the speed of rotation of the vessel much reduced and the accumulated concentrates or heavier constituents 35 discharged from the vessel, the latter action occurring at relatively slow speed of the vessel while the core is being forced to the small end of the vessel in position 40 for commencement of the concentrating period of the next succeeding cycle.
- 45 The pressure to strongly force the core towards the large end of the vessel during concentration, is mostly incident to centrifugal force at high speed of the vessel, on liquid, with its material, being introduced in the small end of the vessel, and as above explained, the pressure of liquid in the cylinder 15, is adjusted to balance this endways pressure throughout the concentrating 50 period, and suitably yield to it as desired, whereas, during the discharge period of the cycle, while the vessel is rotating at a much reduced speed, the endways liquid 55 pressure on the core, as a sequence, is not only greatly reduced, but the centrifugal force then being developed which holds the accumulated concentrates in the vessel is also greatly reduced, these combined 60 changed conditions resulting in the pressure 65

in the cylinder 15, which is maintained constant, then quickly forcing the core to its initial position in the vessel while the accumulated concentrates are rapidly discharged, as has been before stated. 70

As further means for accomplishing the various steps in this operation, I provide the outer end of the cylinder 15, with a secondary chamber 22, connecting with the bore of the cylinder by a passage 23, and supply a suitable valve disc 24, adapted to seat over the passage 23, to close the same, as shown in Fig. 1. 75

The disc 24 is provided with a suitable stem 25, with its end extending through the passage in position to contact with the outer end of the piston head, and open the passage 23, as shown in Fig. 2, at the time the core has substantially reached the extent of its movement towards the large end 80 of the vessel. The disc 24 is normally held in closure by a yieldable member as a rubber cushion 26, suitable for the purpose. 85

As means for automatically supplying liquid under pressure to cause the several 90 members and elements of my invention to function at times and as desired, I provide a hydraulic control, which I will indicate as a whole by the initialing number 27. 95

This control is shown in most parts in plan in Fig. 1, and in vertical cross section in Figs. 6 and 7. It embodies a suitable preferably cast metal frame 28, which is provided with a liquid pressure chamber 100 29, Figs. 6 and 7, for liquid under requisite pressure to hydraulically operate the parts desired. This liquid may be supplied from any appropriate source through a pipe 30, communicating with the pressure chamber. 105

Securely attached to the wall of the pressure chamber 29, and communicating with such chamber are a number of reciprocable plug hydraulic control valves 31, which are indicated in plan in Fig. 1, and will be 110 termed as control valves. They are shown partly in vertical section and partly in elevation in Figs. 6 and 7. In the latter two figures, for purposes of better illustration, while operative, these valves are shown 115 larger than necessary in proportion to some other parts of the control.

The control valves are provided, as above stated, with reciprocable plugs 32, each of which has a liquid port 32' adapted to be 120 normally closed as shown in Fig. 7, but which will be opened for flow of pressure liquid from the chamber 29, when the plug is sufficiently raised, as shown in Fig. 6. The several valves are piped to the various 125 elements, as illustrated in Fig. 1, the functioning of which they control.

As means for operating the control valves, and governing and regulating the times of their respective movements, I pro- 130

vide a slowly rotatable shaft 33, on which are rigidly mounted as many preferably graduated operating cylinders 34, as are required for that purpose, in this instance 5 there being three of such cylinders.

The operating cylinders 34 are partly illustrated in plan in the control in Fig. 1, which closely indicates their relative plan association, but are shown without graduations. They are also shown in operating position in Figs. 6 and 7, but are best shown in detail in Figs. 9 and 11, and their graduations best, in development of the circumferential surface of one of them in 15 Fig. 10.

The graduations are placed on the several cylinders so that the same numbers on each will be in the same axial alignment, in order to better serve as a guide and render 20 quickly possible accurate adjustment or placing relatively and otherwise of the pawl actuating members thereon, which will be herein below explained.

On the circumferential surface of the 25 operating cylinders are located as many movable actuating members 35 as required, for purposes herein below explained. These members are preferably formed suitably to fit the circumference of the cylinders, and 30 are held to place by a suitable bolt 36, which has an elongated head as shown in Fig. 12, adapted to be passed into the annular channels in the cylinders, and clamp the actuating members securely to desired places, such 35 method of clamping being best illustrated in Fig. 11.

When it is wished to move any actuating member to another position or adjust the same on the operating cylinder, its bolt may 40 be loosened and the member moved, and secured rigidly in its changed position by again tightening the bolt.

To transmit movement from the operating cylinders to the valve plugs 32, I provide a lever 37, for each of the valve plugs, 45 which is suitably fulcrumed at 38, Figs. 6 and 7, to part of the control frame 28, with its end nearest the operating cylinder formed into a downwardly extended com- 50 paratively short angle portion, in which is pivoted or hinged a pawl 39, preferably normally positioned as illustrated in Fig. 7, with its outer end in close proximity to, or lying on the peripheral surface of its operating cylinder, adapted to contact with the edge of its actuating member, as the latter 55 is slowly carried in that direction by rotation of the operating cylinders.

The position of these parts in relatively 60 near approaching contact is shown in Fig. 7, and the relative position of the two members is shown in Fig. 6, just after they have functioned and caused movement of the valve plug 32, to a position of opening the

liquid flow port from the pressure chamber 65 29.

It will be seen that forcing the pawl along by the actuating member, will carry with it the deflected or angle end of the valve lever 37, and raise the opposite end of this 70 lever upward, and with it, the valve plug which is suitably attached to that end, preferably by means of a head member 40, in the manner best illustrated in full and dotted lines in Fig. 8.

As means of tripping the pawl to properly release its end from engagement with the edge of its actuating member, there is provided a trip or deflecting member 41, adapted to suitably deflect the other end of the pawl downward during its forced movement backward, which results in raising the contacting end of the pawl upward until it has slid over the top of its actuating member, having in the operation, properly raised 85 its associated valve plug to position of open port, as shown in Fig. 6.

It is desirable to maintain an open flow port through most of the several valves a greater or less length of time during the 90 cycle of operation, depending on what the requirements in that respect may be for the particular element which the valve may be serving.

To accomplish this purpose there is a 95 member 42, illustrated in Figs. 6, 7 and 8, which is hinged or linked in suitable position to that end portion of the valve lever, and is provided with a shoulder or notch, positioned and adapted, as the element 42 100 105 is raised with valve lever, to swing in, and rest on the upper part of the valve structure 43, as shown in Fig. 7, and hold the valve plug up with its port open until released as is below explained.

It will be seen that part of the actuating members 35, are thicker than others, the thinner ones being of suitable thickness to operate the pawl to raise the valve plug sufficiently to open its port, as shown in Fig. 110 7, while the thicker ones are adapted to raise the end of the valve lever and the moving valve parts somewhat higher, as shown in fragmentary Fig. 8, where the member 42, 115 is shown with its shoulder raised somewhat above its contact point illustrated in Fig. 6.

The contact part on this member 42, is so formed or beveled, that when the valve lever is released in the fully raised position shown in Fig. 8, the member will be deflected outward in its downward movement by impact with the frame structure, and permit the valve lever and plug to travel down to their lowest position, which is shown in Fig. 7, thereby closing the flow port through the 120 valve.

The valve plug is provided with a stop collar 44, Figs. 6 and 7, to properly limit its 125

downward movement, and there is a spring 45, to force and hold the plug down in normal position when released by the means for raising the same.

- 5 There is preferably one valve and its mechanism embodied in the automatic control, for each movement of the several elements which it is intended that the control shall cause to function, employing two valves 10 for operation of each of such elements, except in the instance of particular operations through movement of the valve disc 24, Fig. 2, which will be further explained, and in cases where conditions of operation are such 15 as to permit of the coupling of two or more elements to the same valve, entailing simultaneous movement of such elements.

The operating cylinders 34 are each preferably provided with two channels for the 20 actuating members or their bolts, as shown, and the valves 31 are preferably secured to the wall of the pressure chamber 29, in pairs as indicated in Fig. 1, in suitable relation to the channels, so the pawls 39 will properly 25 function with the actuating members to operate their respective valves, as has been above explained.

Any suitable motive power may be employed for the concentrating machine, as an 30 electric motor 46, Fig. 1, which I prefer to have of the variable speed type, directly connected to the counter shaft of the concentrator drive.

This shaft is preferably in two sections, 35 47 and 48 respectively, appropriately mounted in journal boxes as shown and is provided with a suitable friction clutch, as a magnetic clutch 49, properly mounted on the adjacent ends of the shafts, and adapted to 40 frictionally engage and disengage the two parts of the shaft when and as desired.

It will be understood that the core 10, of the concentrator, is operated at a constant speed throughout the successive cycles, and that, as has been already explained, the 45 concentrating vessel, except under unusual special conditions, is operated at a relatively high rate of speed during the concentrating period of each cycle and at a relatively low 50 rate during the concentrate discharge periods.

To obtain the constant speed of the core, its pulley 13, is driven by a belt 50 from a pulley 50', mounted on the constant speed 55 section 47, of the counter shaft.

The preference herein expressed for variable source of power is more especially to facilitate change of speed of the concentrator from time to time to better adapt it to possible radical change in characteristics of material which it may be desired to treat, and not to effect change in speed of the concentrating vessel during its cycles of operation.

65 To automatically decrease the speed of

the concentrating vessel for the concentrate discharge period, which I will term the discharge period, I provide brake mechanism, which preferably embodies a suitable cast metal open end pan member 51, the open 70 end of which is adapted to receive a suitable flexible diaphragm 52, preferably of strong rubber fabric, which is securely and tightly clamped to the open edge of the pan by a ring 53, rendering the pan a closed 75 chamber with a flexible end, adapted to contain liquid under requisite pressure.

To the central portion of the diaphragm is tightly and appropriately secured a stud 54, as illustrated, which is adapted to be 80 forced up or down with movement of the diaphragm.

The pan or base portion 51, is provided with suitable ears 55, which are illustrated in Figs. 1 and 17, located on diametrically 85 opposite sides of the pan, adapted to engage and securely hinge the lower ends of the brake arms 56, which suitably extend upwards, as is most clearly shown in Fig. 17.

The upper end portions of these arms 90 are adapted to carry friction surfaces to operate on a suitable friction wheel or drum 57, securely mounted on the section 48, of the counter shaft, this section being the one which drives the concentrating vessel from 95 a pulley 58, by a belt 58', as shown.

To produce desired movement of the brake arms, there are provided links or members 59, connected in a hinged manner to the upper end of the diaphragm stud 54, 100 and to the respective brake arms, somewhat above their base hinged fastening to the ears 55, as shown in Fig. 17.

Through this form of construction, as the diaphragm is hydraulically forced upwards 105 in the position shown in Figs. 3, 16 and 17, the links 59 will pull the brake arms inward, effecting frictional engagement with the wheel 57, to break down the speed of the section 48 of the counter shaft. 110

This action of the brake will result in reducing the speed of the concentrating vessel as desired, the two parts of the clutch 49, at this time being either entirely disengaged torsionally, or in comparatively weak 115 engagement to permit reduction by the brake of the speed of the section 48 of the counter shaft, with little or no reduction in speed of section 47 thereof.

To maintain a desired approximately uniform reduced speed of the concentrating vessel during the discharge period, there is a governor 60, provided with running mechanism of any suitable ordinary type, preferably variable in operative speed, to which 120 I supply a valve having a reciprocable plug 61, as shown in Figs. 13 and 15, adapted to be operated by the ball mechanism of the governor, to bring the liquid flow port of the plug in registration with the opening 125 130

through the plug barrel 62, thereby opening the valve at high speed of the governor.

During the slow speed of the vessel for discharge of concentrates, it is desired to operate the governor at sufficiently high speed, as illustrated in Fig. 15, in order to open its flow port so far as necessary to render it effective in regulation of flow of liquid to the brake pan, with which it is hydraulically connected.

To best effect this, I provide a centrifugal clutch 63, partly or largely shown in Figs. 1, 13, 15 and 18, which is so constructed as to be effective in driving the governor, at relatively low speed, and ineffective in such respect at high speed.

This clutch embodies a suitable rotating member 64, adapted to carry friction members 65, seated at their sides farthest from the axis, against yieldable cushions 66, as shown.

The rotor 64 of the clutch has an open end, adapted to receive a friction drive pulley 67, mounted on the end of the governor shaft, the relative positions of the clutch and governor being such as to permit the pulley 67, to concentrically enter the opening of the clutch rotor and be driven by the friction members of the latter as best shown in Figs. 1, 15 and 18.

In Figs. 15 and 18, the friction members are shown in contact with the governor drive pulley, operating the governor at high speed, while in Fig. 13, these members are shown somewhat receded, compressing the yieldable members 66, so the governor is at rest, effecting closure of the liquid flow port in its plug.

The torsional contact of the friction members 65 with the governor pulley, occurs while the clutch rotor is operating at insufficient speed to develop centrifugal force necessary to cause such members to compress the yieldable cushion and recede from driving contact with the governor pulley, and ceases when the rotor is being operated sufficiently fast to effect such compression, and cause recession of the friction members from contact with the governor pulley, after which the governor will come to rest, as shown in Fig. 13, which is also the condition illustrated as prevailing in Fig. 1.

It follows that the governor drive clutch, which is intended to be ineffective during the concentrating period, should be more rapidly rotated during that period, and more slowly rotated during the discharge period, as the governor is intended to be potent during the latter period.

To accomplish this, the governor clutch may be driven by a small belt 68, Fig. 1, from the variable speed shaft 48, operating around a pulley 69, on the clutch shaft, thereby affecting the relatively high and low speeds of the clutch at the desired times.

By this manner of driving the governor, from the fact that water under pressure for operating the brake is supplied through it, the speed at which the shaft 48, will drive the governor clutch, as well as the speed at which the concentrating vessel will be permitted through regulation to revolve during the discharge period, may be predetermined and adjusted by means of the governor and otherwise to best suit the requirements of the discharge period, and will be automatically maintained through these mediums, substantially as so predetermined.

During this slow speed period, as has already been explained, the power clutch 49, is either torsionally inert or at relatively low driving torque, and the particular control valve through which pressure liquid is supplied to the governor by the pipe 70, shown in Fig. 1, is open to admit liquid from the pressure chamber 29.

The pipe 71, which connects the governor to the brake pan, is best shown in Fig. 1, as also is a relief pipe 72, from the brake pan, which is preferably provided with a suitable valve to adjust the relief flow passage through the pipe. This relief serves to assist in regulating the effective liquid braking pressure exerted on the brake diaphragm, for maintaining the speed of the counter shaft 48, as predetermined, and as means of requisite escape of water from the pan when the water is closed off from it.

It will be understood that the governor drive clutch, as above stated, is driven from the countershaft 48, and that such shaft during the concentrating period is revolving at comparatively high speed, also that the governor clutch will not be effective in operating the governor while rotating at such high speed, therefore in order to initially reduce the speed of the shaft and vessel where the governor clutch will drive the governor inoperating regulation, I connect the clutch pan, through a branch pipe 70' to one of the control valves, so the brake will initially receive pressure water directly through this valve and not through the governor, to reduce the speed of the shaft 48 and vessel to a point where the governor clutch will drive it to function in regulation as has been explained.

The actuating member which operates the control valve to which the brake is connected for initial pressure water, should be so adjusted as to permit the valve to remain open only a short requisite time, when it should be closed, necessitating the pressure water to the brake for the remainder of the slow speed period, to pass through the governor.

As has already been explained, the section 47 of the counter shaft operates at a practically constant speed, and rotation is imparted from it to the section 48, by the

clutch 49, which in this instance is a magnetic clutch of an appropriate ordinary type.

To make this clutch sufficiently effective 5 when desired to drive the vessel at a concentrating speed, it is strongly energized from any suitable source, not shown, through primary electric wires or conductors 73, which are connected to appropriate 10 ate contact means 74, adapted to be brought into closed circuit by movement of the piston of a hydraulic cylinder 75, carrying wires 76 to close the energizing circuit in the clutch.

15 The wires 76 are in operating engagement with contact rings 77, of the clutch in the ordinary way, as shown in Fig. 1, furthermore, when it is desired to weakly energize the clutch to supply driving torque during 20 the concentrate discharge period, against which the brake with light pressure will readily be effective, the reverse movement of the piston will break the circuit of the strong current and close it with a weak current 25 rent from suitable wires 78, as can be understood through illustration in Fig. 1 of the drawings.

Liquid for operating the hydraulic cylinder 75, is supplied from the pressure chamber 29, through the appropriate valves 31, and the pipe 79, as shown in Fig. 1, as will be hereinafter more fully explained, the particular ones of the valves 31 which control operation of the cylinder 75, are predetermined to function at the respective desired times.

As means for rotating the shaft 33, of the automatic control, which carries the operating cylinders 34, I provide suitable preferable tight and loose pulleys 80, mounted on 40 a shaft which may be revolved from any appropriate source of power, by a belt not shown, which may operate over a drive pulley 81, on said shaft. A belt 82, adapted to 45 operate from the tight and loose pulleys, passes around the pulley 83, which is mounted on the overhanging end of the shaft 33, as shown in Fig. 1, in this manner rotating said shaft.

50 It is desirable that the operating cylinders 34, of the automatic control, in most cases should be revolved only during part of each cycle, for reasons which will be below explained, and for this reason I provide means for stopping and starting such revolution when desired, through medium of a device for shifting its drive belt 82, to alternately operate over the respective tight and loose pulleys 80.

60 This shifting device embodies a suitable hydraulic cylinder 84, positioned and adapted to operate shifting members 85, to move the belt from the tight to the loose pulley, and the reverse, when desired. In 65 the drawings these shifting members are

illustrated as connected directly with the piston rod 86, of the cylinder, but they need not necessarily be of such detail structure.

The end of the cylinder 84, into which pressure liquid enters to operate the mechanism to stop revolution of the shaft 33, is connected through a pipe 87, to one of the control valves, and the functioning of such valve to procure movement of the belt shifter and stop the automatic control, is 70 adjusted and predetermined as desired, as will also be hereinafter more fully explained. It is not necessary to hold this particular control valve open a length of time in its operation, so the member 42, is omitted in 80 this instance, enabling the valve to close quickly when released after being opened.

The reverse movement of this cylinder 84, for starting rotation of the shaft 33, is effected by pressure liquid from the hydraulic cylinder 15, when the valve disc 24, is pressed back through extreme endways movement of the core, this resulting when the core has moved fully to the large end of the concentrating vessel in completion 90 of the concentrating period of the cycle, this movement, requires a time not predetermined, being the sequence of accretion of heavier constituents in the vessel.

A suitable pipe 88 serves to connect the 95 cylinders 15 and 84, as shown in Fig. 1.

During the concentrating period material for treatment properly pulverized and mixed with liquid sufficient to enable it to flow freely, is delivered for feed into the 100 concentrating vessel, through a pipe 89, connecting to a feed valve illustrated mostly in section in Figs. 2 and 4, and which as a whole is indicated by the initialing numeral 90.

The valve 90 embodies a suitable barrel portion 91, with a short open end pipe 92, extending into the small or feed end of the concentrating vessel, as shown in Figs. 1 and 2, terminating therein, in a manner 110 adapted to deposit the material to be operated on, at this end of the vessel in position to here accumulate to the extent desired, in the space between this end of the core and vessel, and, actuated by centrifugal 115 force, to be forced to progressively flow through the channel 14.

In such movement through the channel the desired mineral bearing or other desired heavier constituents are separated and deposited in a progressively forming accretion in said channel, while lighter constituents and liquid pass on through to the large end of the vessel, and out through appropriate discharge holes 93, in the vessel, and 120 are caught by a suitable hood 94, surrounding the large end of the vessel, for this purpose, as shown in Figs. 1 and 2.

The hood is provided with an internal channel or opening in suitable annular 130

alignment with the discharge holes 93 adapted to catch the material discharged through the latter, so the hood will guide the same to its lower portion and out 5 through an opening 95, shown in Fig. 2.

To supply clean or relatively clean water during the concentrate discharge period as desired, there is a pipe 96, communicating with any suitable source of such liquid, not 10 shown, which also connects with the feed valve 90, as illustrated, so when desired while material for concentration is not passing through the valve, such clean water 15 may be flowed through it, into the vessel 15 by means of the pipe 92. The parts of the valve are illustrated in Fig. 2, appropriately positioned for this purpose. While in Fig. 1 they are intended to be in a reverse position, in the manner shown in detail Fig. 4, 20 appropriate for feed of material to the vessel.

Both the pipes for material and water are connected to appropriate sources of supply, not shown, as has been stated, and each is 25 provided with an ordinary appropriate valve, not shown, to regulate the volume of flow through them.

Within the barrel of the valve, as best shown in Figs. 2 and 4, is a valve disc or 30 closing member 97, which is carried in the barrel by a reciprocable rod 98, passing through a valve seat 99', preferably positioned near the longitudinally central internal part of the barrel, as shown.

35 The material feed pipe 89, preferably connects with the upper end of the valve barrel, the opening into such pipe being positioned and adapted to be closed by the valve disc 97, in its full movement in that direction, which position is shown in Fig. 2.

The water pipe 96, is connected to the barrel, as shown, on the opposite side of the valve seat 99', to that of the material feed pipe 89, while the pipe 92, extending into 45 the vessel, is preferably connected on the same side of the seat as is the feed pipe 89. The relative positions of these connections are well shown in Figs. 2 and 4.

To effect movement of the rod 98 carrying the disc 97, for opening and closing the 50 passages in the valve barrel to start and stop flow of material or water through the valve, as desired, I provide a hydraulic cylinder 99, in connected operating conjunction with the valve barrel 90.

This cylinder is formed suitably to serve the purposes intended, as illustrated. It is provided with a piston 100, somewhat elongated, being considerably smaller in diameter 60 throughout its central portion than the bore of the cylinder, and with an enlarged portion at each end appropriate to there form suitable piston members.

The barrel 91, of the valve, and the cylinder 99, are preferably established in such

relative positions as to enable the rod 98, to enter and operate in both of these members, passing through appropriate ordinary packing boxes to prevent leakage at these points. The rod extends sufficiently into the cylinder 70 to connect to the end of the piston 100 therein, so that, as the piston is moved hydraulically, the rod will carry the disc 97, to function in its purposes within the valve barrel. 75

The length of the rod, as well as the spacing of the members and elements of both the valve, and its coordinating cylinder 99, should be such as to properly effectuate the purposes intended. 80

As means for hydraulically moving the members of the cylinder 99, for operating the feed valve, and to time, control, and regulate such movements as desired with relation to other steps in operation of my invention, I provide the cylinder 99 with suitable hydraulic pipes 101 and 102, connected in position to supply pressure at their respective ends of the piston 100, as best shown in Figs. 2 and 4, the pipe 101 being employed when it is desired to stop flow of liquid and start flow or feed of material to the concentrating vessel, by moving the valve disc 97, as shown in Fig. 4, which is intended to be the position of these parts during the concentrating period, the relative positions of the members of the concentrating machine being shown in Fig. 1, as appropriate for commencement of this period, and the pipe 102, is employed during the concentrate discharge period, when feed of material is stopped and relatively clean liquid introduced, as has been before stated, this position is illustrated in Fig. 2. 95

The pipes 101 and 102 are each intended to be connected to one of the control valves 31, as is shown in Fig. 1, and the particular actuating members 35, which operate these valves are to be positioned and adjusted on the circumference of the operating cylinders 110 34, suitably to cause the respective valves 31, serving these pipes to function relatively, as well as with relation to other steps and movements in the cycles of operation, to effect feed of material and water to the 115 vessel, through the mediums which have been explained, as and at the times desired. 120

As means of releasing the water which may be static in the full end of the hydraulic cylinder 99, when it is desired to force a 125 reverse movement of the piston 100, by admission of pressure liquid in the opposite end, I provide an escape pipe 103, as shown in Figs. 2 and 4, and through both of the enlarged ends of this piston, I provide a 125 comparatively small opening 104, indicated in dotted lines in Figs. 2 and 4, and shown in plan in Fig. 5, which will serve as means of desired relief and escape for such liquid, but are too small with relation to the pres- 130

sure pipes 101 and 102, to materially effect the prompt movement of the piston.

The escape pipe should be located in the central portion of the hydraulic cylinder 5 so at all times to be positioned between the large ends of the piston, as shown in Figs. 2 and 4.

The hydraulic cylinders 75 and 84, both appearing in Fig. 1, are of the same internal 10 construction as the cylinder 99, which is clearly illustrated in Figs. 2 and 4, although the cylinder 99 is of different size than the others, it therefore does not appear necessary to further illustrate them, 15 also their relief pipes appear obvious without initialing them.

The concentrating machine structure embodies a suitable bed plate 105, on which its other appropriate parts are mounted, 20 and other coordinating elements and members entering into my invention are suitably relatively positioned and appropriately mounted to operate, and coordinate to effect the results desired.

25 It will be understood that the shaft 33, of the automatic control with its operating cylinders 34, is intended to be revolved one revolution during each complete cycle of the concentrating machine, and in predetermined relative times during such revolution to perform its purpose in effecting suitable function desired, these separate and relative movements being predetermined and relatively timed by the position which 30 the several actuating members 35, are secured on their respective operating cylinders.

The speed of revolution or movement 40 of the shaft 33, is fixed to best suit the particular operation, and unless the conditions of the operation materially change, such speed preferably remains the same, whereas the length of the concentrating period of each cycle, is not predetermined, 45 but is automatically determined by the length of time required to progressively accumulate a load or quantity of concentrates in the concentrating channel, sufficient to gradually and automatically force the core 50 member to its fullest extent towards the large end of the vessel, and open the valve disc 24, as shown in Fig. 1.

This length of time may be effected by several causes, one potent cause being the 55 content of a greater or less proportion of concentrates or heavier constituents in the material being treated, resulting in more or less quickly forcing the core back to completion of the concentrating period, and another being the feed of a greater or less 60 volume of material to the vessel, which will produce a similar effect.

To compensate this condition, the shaft 33 of the control is automatically stopped 65 after causing the feed of material to be

started at the beginning of the concentrating period, and remains at rest until automatically started, through opening of the valve disc 24, at the completion of the concentrating period, as shown in Fig. 2, when 70 the belt 82 will be shifted and the control will again function, as the shaft 33 is revolved, until again stopped as above explained.

It will be seen that the belt shifting cylinder 75, is connected to one of the control valves by a pipe 106, to enable the control, being properly adjusted, to function and shift the belt to stop the shaft 33, at the appropriate times. 75

In operation, assuming the necessary pressure water for use through the hydraulic control valves, and for other purposes, as well as other operating requisites have been properly provided, and the various actuating elements 35, have been positioned on their operating cylinders of the automatic control to effect the several steps and movements in the cycles, at times and otherwise as desired, the power for operation having 80 been started, the magnetic clutch is then fully energized through proper movement of mechanism of the hydraulic cylinder 75, to close the strongly energizing circuit, rendering the clutch effective to revolve the 85 section 48 of the counter shaft, and the concentrating vessel at relatively high speed.

If the driving motor is of a variable speed type, its speed is adjusted as desired, but otherwise the respective belt pulleys may 90 be proportioned to obtain the comparatively high rotation of the concentrating vessel desired for best serving the concentrating period, the core of the concentrator being 95 revolved at a suitable different speed to that of the vessel, usually at a lesser speed, this somewhat depending on the requirements of the material being operated on, the slower speed often serving best on materials composed largely of comparatively coarse 100 grains. 110

As has already been explained, the core 10, at the commencement of the concentrating period, is positioned at the small end of the vessel, contracting the flow or concentrating passage to its smallest normal size. 115

Under the above conditions, feed of material is started to the vessel through functioning of the particular control valve by which the feed valve is operated, and the 120 material, including its carrying liquid as fed into the vessel, will accumulate to the extent necessary for operation in the space between the small end of the vessel and that end of the core, and will be forced to flow 125 through the concentrating passage towards the large or discharge end of the vessel.

This material and liquid passing through the channel, will keep it filled so that the liquid will contact with pressure against 130

the circumferential surface of the core, and from the fact that this surface is revolving at a speed different from the adjacent surface of the vessel, there will be a frictional wash or scrubbing current generated through medium of the liquid in the channel, which should be developed to strength, largely controlled through the differential speed of the vessel and core, to prevent the relatively lighter constituents of the material from assuming fixed lodgment in the channel, and to carry or flow them on through to discharge, while permitting the desired relatively heavier constituents, under the impetus of centrifugal force, to lodge in the channel, and to progressively form in a bed or accretion therein.

As this accretion forms, gradually contracting the flow channel, the pressure of accumulated feed in the small end of the vessel will increase, resulting in gradually and progressively forcing the core towards the large end of the vessel to make room in the channel for the lodging concentrates, as well as maintaining a practically uniform appropriate flow passage, until the core has reached its extreme position towards the large end, and has pressed back the valve disc 24, permitting flow through the pipe 88, to hydraulically operate the belt shifting cylinder 84, for starting the shaft 33, so that the valve 31 which controls the material feed devices will quickly function and effect stoppage of feed of material and start feed of water to the vessel.

The concentrating speed of the vessel is preferably maintained under these conditions, a short time after the feed of material has been stopped and that of water started, sufficient to enable the lighter constituents of the material then in passage through the vessel to pass out to discharge, being followed and replaced by the relatively clean water, leaving the substantially clean concentrates bedded in the concentrating passage.

The position of the actuating member which causes the particular valve to function, controlling opening of the strongly energizing current to the magnetic clutch, and closing the circuit of the weaker current, is such that at this time it will become effective, so the section 48 of the counter shaft will be readily amenable to the action of the brake in reducing and regulating the speed under the then weak torsional energy of the clutch, and the frictional impetus engendered by the wash in the concentrating passage.

The control valve through which pressure water is initially supplied to the brake, now opens, rendering the brake effective to reduce the speed of the shaft 48, and the vessel sufficiently for the governor to become effec-

tive in regulation, when such control valve 65 closes and the control valve connected to the governor opens, so that water will then become effective through the governor, in operation of the brake, reducing rotation of the shaft 48, and the vessel, to the speed predetermined, at which the governor will regulate, and substantially maintain these parts during the concentrate discharge period.

As has been before explained, the governor, through medium of the clutch 63, is driven from the shaft 48, and that this clutch is not frictionally effective during high speed of rotation, but becomes so for driving the governor to effect regulation, as soon as the brake sufficiently reduces the speed of the shaft 48, and that of the vessel, at commencement of the discharge period, as just above explained, such reduction occurring after the driving torque of the power clutch 49 has either been stopped, or 85 sufficiently reduced to permit.

The regulation by the governor will continue so long as its driving clutch is maintained at requisite low speed, and at the same time, so long as water is supplied 90 through the governor with which to operate the brake.

Under such conditions the brake, regulated by the governor, will not permit the shaft 48, and vessel to increase in rotation 95 sufficiently to render the governor clutch ineffective, or beyond requirements of the discharge period, consequently in order to enable acceleration for concentration at the desired predetermined time at the end of the 100 discharge period and before the power clutch is highly energized to requisite torque for accelerating the speed of the vessel, the control valve through which water is being supplied to the governor, is timed to function, stopping the flow of such braking water, primarily to the governor and secondarily to the brake, rendering them both ineffective through this medium so long as that control valve remains in closed position, 105 which is so maintained throughout the concentrating period, after which as has already been explained, the speed of the vessel is again sufficiently reduced for commencement of a succeeding discharge period.

As a sequence to lowering the speed of the concentrating vessel, the centrifugal force on the bedded concentrates or heavier constituents becomes greatly reduced, rendering the same much more easily dislodged and discharged. Such force is also reduced on the liquid, which effect largely lessens the endways pressure on the core, while the opposing pressure on the core, exerted by the liquid in the cylinder 15, remains substantially constant, so that the latter pressure then being the greatest forces the core to move with comparative rapidity to the 115 120 125

small end of the vessel into its initial position ready for commencement of the concentrating period of another cycle.

During this return movement, the core 5 assists the liquid in dislodging and flowing the bedded concentrates to discharge through the hole out of which the separated relative lighter constituents passed during concentration, but however, the concentrates may 10 be diverted to such place as desired by any appropriate means, not shown, as the same flow from the discharge opening 95, in the hood of the concentrator.

The concentrates are readily and rapidly 15 removed under the above stated conditions, from the fact that while then under influence of comparatively low centrifugal force, they are subjected to highly developed hydrous washing force in the flow channel, 20 as a result of the slow revolution of the vessel, and the relatively high or constant revolution of the core. For a tentative illustration it may be explained that in operation concentrates have been discharged 25 in quantity exceeding one thousand pounds within a period of approximately one minute, without stopping rotation of the concentrating vessel.

It will be understood that the control 30 valve, to supply water to the cylinder which causes the energizing current of the power clutch to be changed, as well as the control valve causing operation of the feed valve, should be timed to suitably function 35 to carry out these respective steps of the cycle, as also the valves controlling other steps of operation should be timed and adjusted to effect desired coordination in performance of the elements herein embodied 40 and the proper carrying out of my invention.

What I regard as new and desire to secure by Letters Patent is:—

1. In a concentrating plant for treatment 45 of finely divided materials having constituents of different degrees of specific gravity, while mixed with liquid, the combination of a concentrating element embodying a rotatable concentrating vessel adapted to operate in cycles, each embracing a period of collecting a quantity of heavier constituents at high speed and then discharging the same at relatively low speed of the vessel, and a core member adapted to operate at practically constant speed throughout said cycle, means for effecting such constant speed of the core, means for effecting such relatively high speed of the vessel, means for effecting and maintaining such low speed of the vessel without stoppage during the discharge period, and means for automatically functioning said several operations of the vessel, and core, governed in part by accretion of heavier constituents in the vessel, 55 substantially as described.
2. In a concentrating plant for treatment of finely divided materials, having constituents of different degrees and specific gravity, while mixed with liquid, the combination of a concentrating element having 70 a rotatable concentrating vessel, adapted to operate in cycles, each embracing a period of collecting a quantity of heavier constituents and then discharging the same, means for feeding material for treatment into the 75 concentrating element during an undetermined period of such cycle, governed by accretion of heavier constituents in the concentrating element, means for feeding relatively clean liquid in said element for discharging the accretion of heavier constituents within predetermined time in said cycle, and means for functioning the several members of the plant in the operation thereof, 80 substantially as described. 85
3. In a concentrating plant for treatment of finely divided materials having constituents of different degrees of specific gravity, while mixed with liquid, the combination of a concentrating element adapted to operate in cycles each embracing a period of collecting a quantity of heavier constituents and then of discharging the same, means for feeding material for treatment into the concentrating element for a period 95 governed by accretion of heavier constituents in the concentrating elements, means for discharging the accretion of heavier constituents from said element during each cycle, and means for functioning the several members of the plant in operation thereof, 100 substantially as described. 105
4. In a concentrating plant for treatment of finely divided material having constituents of different degrees of specific gravity 110 while mixed with liquid, the combination of a concentrating element adapted to be operated in cycles of collecting a quantity of heavier constituents and then discharging the same, means for feeding material for treatment into the concentrating element, automatically governed by accretion of heavier constituents in the concentrating element, means for feeding relatively clean liquid to said elements for discharging the accretion of heavier constituents within time predetermined by automatic governing mechanism, and adjustable automatic means adapted to causing the several members of the plant to function, which effect operation of said concentrating element, 115 substantially as described. 120
5. In a concentrating plant for treatment of finely divided materials having constituents of different degrees of specific gravity, 125 while mixed with liquid, the combination of a centrifugal concentrating element, adapted to operate in cycles, and having a rotatable concentrating vessel adapted to collect a quantity of heavier constituents at 130

- a comparatively high speed and discharge the same at a comparatively low speed, means for feeding material to said vessel at high speed for an undetermined time, 5 governed by accretion of heavier constituents in the vessel, means for effecting discharge of heavier constituents during a predetermined period of slow speed of the vessel, means for rotating the vessel at high 10 speed for the undetermined period for concentration, means for slowly rotating said vessel for a predetermined period for discharging heavier constituents, and means for functioning the several elements of said 15 plant during operation, substantially as described.

6. In a concentrating plant for treatment of finely divided materials, having constituents of different degrees of specific 20 gravity, while mixed with liquid, the combination of a centrifugal concentrating element having a rotatable concentrating vessel adapted to operate in cycles, each embracing a period of collecting a quantity of heavier 25 constituents at a comparatively high speed; and a period of discharging the same at a comparatively low speed, means for feeding material to said vessel at high speed for an undetermined time, governed by accretion of heavier constituents in the vessel, 30 automatic means governed in part by accretion of heavier constituents in the vessel, for effecting low speed of the vessel, means for rotating the vessel at high speed during 35 an undetermined period of the cycle and at low speed during a predetermined period of the cycle, and means for functioning the several elements of the plant during operation, substantially as described.

40. 7. In a concentrating plant for treatment of finely divided material, having constituents of different degrees of specific gravity, while mixed with liquid, the combination of a centrifugal concentrating element 45 adapted to operate in cycles, having a rotatable concentrating vessel adapted to collect a quantity of heavier constituents at a comparatively high speed during each cycle, and discharge the same at a comparatively 50 low speed during each cycle, means for feeding material to said vessel, at high speed for an undetermined time, governed by accretion of heavier constituents in the vessel, an automatic control member, governed in part 55 by accretion of heavier constituents in the vessel, adapted to effect functioning of means for introducing feed of material to the vessel, and stopping said feed; for reducing the power torque driving the vessel; 60 and for operating the vessel at slow speed for a predetermined time for discharge of heavier constituents and means for supplying operating power to said plant, substantially as described.
65. 8. In a concentrating plant for treatment

of finely divided material, having constituents of different degrees of specific gravity, while mixed with liquid, embodying a centrifugal concentrating element adapted to operate in cycles embracing separate periods 70 of accumulating heavier constituents and then discharging the same, having a concentrating vessel adapted to be operated at relatively high speed for concentration during an undetermined period of the cycle and at a relatively slow speed during the concentrate discharge period of said cycle, and a differentially rotatable core member adapted to operate at a practically constant speed throughout the cycle, in combination 75 with a substantially constant speed power element, an automatic control member, in part governed by accretion of heavier constituents in the vessel, adapted to effect functioning of means for accelerating the vessel for concentrating speed; for supplying feed of material to the vessel and discontinuing such feed and supplying relatively clean water to the vessel, and discontinuing the same; for reducing and maintaining the concentrating vessel at relatively low speed during the discharge period, and means for maintaining the speed of the core member at a practically constant speed 80 throughout the cycle, substantially as described.

9. In a concentrating plant for treatment of finely divided material, having constituents of different degrees of specific gravity, while mixed with liquid, embodying a concentrating element adapted to operate in cycles each embracing concentrating period and a discharge period of heavier constituents, and having a concentrating vessel adapted to be rotated at relatively high speed during the concentrating period, and at a relatively slow speed during said discharge period, and a differentially rotatable core member adapted to operate at a practically constant speed throughout the cycle, 100 in combination with an automatic control member, adapted to effect functioning of means for accelerating the vessel for concentrating speed; for supplying feed of material to the vessel and discontinuing such feed; means for supplying relatively clean water to the vessel for discharging heavier constituents; and means for reducing and maintaining the concentrating vessel at relatively requisite low speed during the discharge period, substantially as described.

10. In a concentrating plant for treatment of finely divided material, having constituents of different degrees of specific gravity, while mixed with liquid, embodying a concentrating element adapted to operate in cycles each embracing an undetermined concentrating period and a discharge period of heavier constituents, and having a concentrating vessel adapted to be rotated at 110

- relatively high speed during the undetermined concentrating period, and at a relatively slow speed during said discharge period, and a differentially rotatable core member adapted to operate at a practically constant speed throughout the cycle, in combination with an automatic control member, adapted to effect functioning of means for accelerating the vessel for concentrating speed; means for supplying feed of material to the vessel and discontinuing such feed; means for supplying relatively clean water to the vessel for discharging heavier constituents; for reducing and maintaining the concentrating vessel at relatively requisite low speed during the discharge period, embodying a governor connected to said automatic control, adapted to supply liquid under pressure to a hydraulic brake for engaging means driving the concentrating vessel, and means for maintaining the speed of the core member at a practically constant speed throughout the cycle, substantially as described.
11. In a concentrating plant for treatment of finely divided material, having constituents of different degrees of specific gravity, while mixed with liquid, a concentrating element adapted to operate in successive cycles, each embracing a period of accumulating and then discharging a quantity of heavier constituents, embodying a concentrating vessel adapted to be operated at relatively high speed during an undetermined concentrating period in said cycle, and at a relatively slow speed during a predetermined period in said cycle for discharge of heavier constituents, and a core adapted to be rotated at a practically constant speed throughout the cycle, in combination with means for driving said concentrating element embodying a shaft, with means for operating the same at requisite constant speed, and provided with transmission means for operating said core member at a predetermined speed, and a shaft in extended axial alignment with said shaft, having transmission means for operating said vessel, said former shaft provided with the driving member of a clutch, positioned and adapted to torsionally drive a member of said clutch mounted on the latter shaft, automatic means in part governed by accretion of heavier constituents within the vessel for effecting variation in the torsional energy of said clutch, means for automatically controlling the speed of the concentrating vessel at reduced rotation during the discharge period, and means for accelerating the vessel for concentrating speed, substantially as described.
12. In a concentrating plant for treatment of finely divided material having constituents of different degrees of specific gravity, while mixed with liquid, the combination of a concentrating element adapted to operate in cycles of undetermined duration, of collecting a quantity of heavier constituents, and then of discharging the same, embodying a concentrating vessel adapted to rotate at relatively high speed during an undetermined concentrating period in said cycle, and at a relatively low speed for a predetermined period of said cycle for discharge of heavier constituents, means for effecting such speeds, and an automatic control member for controlling the functioning of said latter means, adapted to operate in cycles of predetermined time, being less than the undetermined length of the cycle of the concentrating element, and to be stopped for the remainder of the undetermined cycle, means embodied in said control for effecting stoppage thereof, and means governed by accretion of heavier constituents in the vessel for starting said control at the end of the concentrating period, substantially as described.
13. In a concentrating plant for treatment of finely divided materials having constituents of different degrees of specific gravity, while mixed with liquid, the combination of concentrating element adapted to operate in cycles each embracing a period of collecting a quantity of heavier constituents, and a period of discharging such constituents, embodying a concentrating vessel adapted to operate at a relatively high speed during an undetermined concentrating period in said cycle, and at a relatively low speed for a predetermined discharge period in said cycle, an automatic control member adapted to operate in cycles of predetermined time, being less than the undetermined length of the cycle of the concentrating element, and to be stopped for the remainder of such undetermined cycle, means embodied in such control for effecting the stoppage thereof, means governed by accretions of heavier constituents in the vessel for starting said control at the end of the concentrating period, means for effecting the relative high and low speeds of the concentrating vessel, hydraulically connected to valves embodied in said automatic control, adapted to effect functioning of said latter means, and adjustable means embodied in said control for effecting operation of said valves, substantially as described.
14. In a concentrating plant for treatment of finely divided materials having constituents of different degrees of specific gravity, while mixed with liquid, the combination of a concentrating element adapted to operate in cycles of successively collecting a quantity of heavier constituents and then discharging the same, embodying a concentrating vessel adapted to operate at relatively high speed during concentration for an undetermined period, and at relatively

low speed for a predetermined period for discharge of heavier constituents, an automatic control member adapted to operate in cycles of predetermined time, being less than the undetermined time of the cycle of the concentrating element, and to be stopped for the remainder of the undetermined cycle, means embodied in such control for effecting stoppage thereof, means governed by acceleration of heavier constituents in the vessel for starting the control at the end of the concentrating period, means for effecting the high and low speed of the concentrating vessel, hydraulically connected to valves in the automatic control, embodying governor and brake mechanism for automatically maintaining requisite low speed of the concentrating vessel during the discharge period, and adjustable means embodied in said control for effecting operation of said valves, substantially as described.

15. In a concentrating plant for treatment of finely divided materials, having constituents of different degrees of specific gravity, while mixed with liquid, the combination of 25 a rotatable concentrating element, embodying a concentrating vessel adapted to operate in cycles, each embracing a period of collecting a quantity of heavier constituents, at high speed, and a period of discharging said 30 constituents at relatively low speed, means for effecting said high and low speeds of the vessel, and an automatic control member embodying control valves, adapted to govern liquid under pressure for causing functioning of the means for effecting said high and 35 low speeds, provided with means for maintaining such valves in open position for a predetermined period, and adjustable means for operating said valves, substantially as 40 described.

ORRIN B. PECK, JR.
